UNITED STATES PATENT OFFICE.

FREDERICK P. MARX, OF ST. LOUIS, MISSOURI.

SHANK SUPPORT.

Application filed August 24, 1921, Serial No. 495,098. Renewed February 4, 1924.

To all whom it may concern:

Be it known that I, FREDERICK P. MARX, a citizen of the United States, residing at the city of St. Louis and State of Missouri, have 5 invented a new and useful Shank Support, of which the following is a specification.

This invention relates to shank supports.

An object of the invention is to provide an improved supporting member supported 10 by and extending forwardly from the shoe heel and possessing the desired characteristic of solidity and at the same time retaining the desired flexibility of the shoe sole beyond the forward end of the support.

15 Another object of the invention is to provide an improved shank support built into the heel and extending forwardly to form a connection with the shank of the shoe sole and having rigid connection with the heel.

20 Other objects will appear from the following description reference being made to the accompanying drawing, in which

Fig. 1 is an elevation showing my improved shank support in connection with 25 a shoe.

Fig. 2 is a longitudinal vertical section through the heel and the shank support.

Fig. 3 is a vertical cross section on the line 3—3 of Fig. 2.

25 Fig. 4 is a plan view of the shank support detached from the heel and the shoe.

As shown my improved shank support comprises a metallic heel formed to provide a relatively wide and deep rear portion 1 and a relatively narrow and shallow forward portion developing into a substantially flat end portion 2. The material may be cast or otherwise formed in the desired shape.

40 The upper edges of the flaring walls of the device are provided with an outwardly extending flange 3 adapted to be secured to the shoe sole or to the heel by nails 4 passing through holes in said flange and engaging 45 the sole or the heel, as desired.

The wide and deep part 1 of the device is seated in a recess formed in the shoe heel while the bottom wall of the device inclines upwardly toward the shank of the shoe sole 50 in front of the heel.

In making connection the shank support may be secured directly to the shoe sole or directly to the heel as desired. In case the device is secured to the heel the nails 4 are 55 driven through the flange 3 into the heel as shown in Fig. 3. In case the device is se-

cured directly to the shoe sole the nails 4 are driven through the flange 3 into and clenched upon the shoe sole as shown in Fig. 2.

In either case the shank of the shoe sole is preferably split horizontally or transversely to provide an under portion 5. The rear extremity of the end portion 5 is extended into the recess in the shoe heel (Fig. 2) below the shank support and forms a cover for the shank support from the forward end to a point behind the breast wall of the heel.

If desired nails 6 may be used to bind the forward end of the shank support in connection with the shoe sole.

My improved shank support is adapted for use in connection with heels of various types. It may be used in connection with leather heels as shown, and may as readily be used in connection with rubber heels or heels composed of any material.

The nails 7 by which the heels are fastened to the shoe sole are at the sides of the shank support and, since the shank support is imbedded in the heel, it is impossible for any of the parts to become relatively displaced.

I do not restrict myself to unessential features, but what I claim and desire to secure by Letters Patent, is:—

1. The combination with a shoe heel having a recess therein, of a shank support comprising a concave portion seated in the recess of the heel, and a forwardly extending narrow portion comprising upwardly and outwardly flaring walls in continuation of the walls of the concave portion converging toward their forward ends, said narrow portion extending forwardly from the heel and forming a rigid support for the shank of the shoe sole.

2. The combination with a shoe heel having a recess therein, of a shank support comprising a concave portion seated in the recess of the heel, a forwardly extending narrow portion comprising upwardly and outwardly flaring walls in continuation of the walls of the concave portion converging toward their forward ends, said narrow portion extending forwardly from the heel and forming a rigid support for the shank of the shoe sole, and an under cover for the forwardly extending portion of the shank support having its rear end attached to the heel.

3. The combination with a shoe heel, of a shank support composed of thin metal shaped to provide a relatively wide concave rear portion imbedded in the heel, and a forwardly extended portion narrowing toward its forward end and having upwardly flaring walls in continuation of the walls of the rear portion, which walls converge and flatten toward the forward end of the shank support.

4. The combination with a shoe heel, of a shank support composed of thin metal shaped to provide a relatively wide concave rear portion imbedded in the heel, a forwardly extended portion narrowing toward its forward end and having upwardly flaring walls in continuation of the walls of the rear portion, which walls converge and flatten toward the forward end of the shank support, and a flat portion extending forwardly from the termination of the space between said flaring walls.

5. The combination with a shoe heel, of a shank support composed of thin metal shaped to provide a relatively wide concave rear portion imbedded in the heel, a forwardly extended portion narrowing toward its forward end and having upwardly flar-

ing walls in continuation of the walls of the rear portion, which walls converge and flatten toward the forward end of the shank support, and a bordering flange extending outwardly from the upper edge of said support to bear against the shoe sole.

6. A shank support of the character described, comprising a thin metallic body including a concave rear portion, the concavity of which is of gradually decreasing depth toward the forward end thereof, and a narrow front portion which is downwardly concaved in cross section in continuation of the concavity of the rear portion arranged to support the shank of a shoe sole.

7. A shank support of the character described, comprising a thin metallic body including a concave rear portion, the concavity of which is of gradually decreasing depth toward the forward end thereof, a narrow front portion which is downwardly concaved in cross section in continuation of the concavity of the rear portion arranged to support the shank of a shoe sole, and a relatively flat extremity at the forward end of said front portion.

FREDERICK P. MARX.
